United States Patent

Des. 235,570
Patented June 24, 1975

235,570

TOY CONSTRUCTION PIECE

Stanley Ernest Barton, McKinnon, Victoria, Australia,
assignor to Rosenhain and Lipmann Pty. Limited,
Richmond, Victoria, Australia

Filed Apr. 3, 1973, Ser. No. 347,511

Claims priority, application Australia Nov. 22, 1972

Term of patent 14 years

Int. Cl. D21—01

U.S. Cl. D34—15 GG

FIG. 1

FIG. 2

FIG. 1 is a top perspective view of a toy construction piece showing my new design; and FIG. 2 is a bottom perspective view thereof.

The depth of the slot openings appearing on the top face of FIG. 2 are effectively the same as the height of the extension shown in FIG. 1.

I claim:

The ornamental design for a toy construction piece, as shown and described.
